United States Patent Office

Des. 192,433
Patented Mar. 20, 1962

192,433

EXERCISER, OR SIMILAR ARTICLE

Richard J. Harwood, P.O. Box 1212, Wichita, Kans.

Filed Oct. 27, 1961, Ser. No. 67,281

Term of patent 14 years

(Cl. D34—5)

FIG. 1

FIG. 2

FIG. 3

FIG. 4

FIG. 1 is a side elevation view of an exerciser showing my new design.

FIG. 2 is a front elevation view of same.

FIG. 3 is a top view of same.

FIG. 4 is a rear view of same.

The side opposite to that of FIG. 1 is the same in appearance.

I claim:

The ornamental design for an exerciser, or similar article, as shown and described.
